(57) CLAIM

The ornamental design for a high top sneaker with a pair of gores, as shown and described.

DESCRIPTION

FIG. 1 is a front right perspective view of a high top sneaker with a pair of gores;

FIG. 2 is a front left perspective view of a high top sneaker with a pair of gores;

FIG. 3 is a top view of a high top sneaker with a pair of gores;

FIG. 4 is a bottom view of a high top sneaker with a pair of gores;

FIG. 5 is a front view of a high top sneaker with a pair of gores;

FIG. 6 is a back view of a high top sneaker with a pair of gores;

FIG. 7 is a right-side view of a high top sneaker with a pair of gores; and,

FIG. 8 is a left-side view of a high top sneaker with a pair of gores.

The broken lines depict stitching that forms a part of the claimed design.
